UNITED STATES PATENT OFFICE

154,847

DESIGN FOR A COMBINATION BOAT AND LAND VEHICLE BODY

Merl J. Harkless, Syracuse, Ind., assignor to Liberty Coach Company, Inc., Bremen, Ind., a corporation of Indiana

Application September 16, 1948, Serial No. 148,612

Term of patent 14 years

(Cl. D71—1)

To all whom it may concern:

Be it known that I, Merl J. Harkless, a citizen of the United States, and a resident of Syracuse, in the county of Kosciusko and State of Indiana, have invented a new, original, and ornamental Design for Combination Boat and Land Vehicle Body, of which the following is a specification, reference being had to the accompanying drawing, forming part thereof.

In the drawing:

Fig. 1 is a perspective view of the new combination boat and land vehicle body design, looking from a point rearward and to the starboard side thereof;

Fig. 2 is a view in elevation of the port side of the vehicle, the opposite side being complementary and therefore similar thereto;

Fig. 3 is a top plan view;

Fig. 4 is a front elevation; and

Fig. 5 is a rear elevation.

The dotted line representations of flag staffs or radio masts shown in connection with the combination boat and land vehicle in Fig. 1 are purely for illustrative purposes.

I claim:

The ornamental design for a combination boat and land vehicle body, substantially as shown and described.

MERL J. HARKLESS.
